United States Patent Office

Des. 222,425
Patented Oct. 26, 1971

222,425

WRENCH

Franz Palfi, 122 West St., Battle Creek, Mich. 49017

Filed Nov. 9, 1970, Ser. No. 25,899

Term of patent 14 years

Int. Cl. D8—05

U.S. Cl. D8—29

FIG. 1 is a front view of the wrench embodying my new design.

FIG. 2 is a side elevation thereof.

FIG. 3 is a top view thereof, with the arms shown broken away for ease of illustration.

FIG. 4 is a bottom view thereof.

I claim:

The ornamental design for a wrench, substantially as shown.
